BOBBY PIN DISPENSER AND REFILLING
MEANS

Philip A. Avelli, Richmond Hill, N. Y.

Application January 4, 1949, Serial No. 69,194

4 Claims. (Cl. 132—1)

1

This invention relates to magazines and dispensers for bobby pins, hairpins and the like, which are capable of being refilled or loaded with groups or packs of such pins, and refers particularly to a bobby pin dispenser.

The main object of the present invention is to provide a bobby pin dispenser for dispensing the pins individually therefrom in convenient manner, and thereby avoiding confusion and loss of time when arranging the hair.

Another object is to provide loading or refilling means for loading a dispenser as mentioned with a new supply of bobby pins in a single filling operation.

A further object is to provide a form of dispenser which may be conveniently loaded by inserting a refill package of bobby pins as obtainable on the market, so that the dispenser when closed upon the inserted pack is instantly ready for dispensing pins therefrom.

Other objects and advantages of the invention will appear in further detail as the specification proceeds.

In order to facilitate ready comprehension of this invention for a proper appreciation of the salient features thereof, the invention is illustrated on the accompanying drawings forming part hereof, and in which:

Figure 1 is a front elevation of the bobby pin dispenser made according to the invention and embodying the same in a practical form;

Figure 2 is a side elevation of the same bobby pin dispenser as seen from the left in Figure 1;

Figure 3 is another side elevation of the same bobby pin dispenser as seen from the right in Figure 1;

Figure 4 is a vertical section taken on line 4—4 in Figure 3;

Figure 5 is a fragmentary section which is partially a duplication of a portion of Figure 4 to illustrate a changed relation of parts;

Figure 6 is a bottom plan view of the dispenser of Figure 1, as seen from below in that figure;

Figure 7 is a side elevation of a manually-operated bobby pin dispensing member of the device illustrated in Figures 1 to 6;

Figure 8 is a plan view of the same bobby pin-dispensing member as shown in Figure 7;

Figure 9 is a front elevation of a modification of the bobby pin dispenser of Figures 1 to 6;

Figure 10 is a transverse section of the bobby pin dispenser of Figure 9, as taken on line 10—10 of said figure;

Figure 11 is a perspective view of a bobby pin refill frame adapted to be inserted with a stack of

2

bobby pins therein into the dispenser of Figures 9 and 10;

Figure 12 is a front elevation of a modification of the loading device;

Figure 13 is a bottom plan view of the same loading device as shown in Figure 12, and as seen from below in that figure.

Throughout the views, the same reference numerals indicate the same or like parts.

10 When arranging the hair, women universally insert bobby pins, if such are used, but all too frequently the pins are mixed with other types of pins, or jumbled together in a tray, or even lie in a heap, which conditions obviously interfere with the hair-dressing operation, due to the frequent stoppages necessary for extracting simple pins from the tray or heap.

Upon considering this problem, it has occurred to me that an effective dispenser for bobby pins should be available which makes it convenient and simple to dispense bobby pins therefrom, one by one, as needed. As a result, I have succeeded in producing a bobby pin dispenser which is not only capable of dispensing single bobby pins therefrom in convenient manner, but is also convenient to refill with the new supply of such pins when required, as will now be more fully described.

Hence, in the practice of my invention, and referring again to the drawings, a bobby dispenser, generally indicated at 18, primarily includes a container or magazine 19 having a front wall 20, end walls 21 and 22 and a bottom 23, which at the left end terminates a predetermined distance from the end wall 21 to provide a bottom delivery opening 24, as will be more clearly defined hereinafter. In the front wall 20 is a large rectangular opening or slot 25 which extends down to within a short distance of the bottom and is of such width that the two marginal portions 26 and 27 of front wall 20, which are disposed at either side of the mentioned opening, give free access to the interior of the container when open. In the inner sides of the marginal portions 26 and 27 of the front wall are a pair of rabbets or vertical slots 28, 29 serving to receive corresponding tongues 30, 31 of a vertically-slidable front door 32 which depends rigidly from a top 33 which serves as a cover for the container and extends flush with the front door 32 and the upper portions of marginal sections 26 and 27 of the front wall 20 and terminates at the sides or ends thereof flush with the end walls 21 and 22 and also rearwardly flush with the rear wall 34 of the container which is joined to the end

walls 21 and 22. The arrangement is such that if the top or cover 33 is raised directly upward, the front closure 32 will slide upwardly in rabbits or slots 28 and 29 of the marginal portions 26 and 27 until closure member 32 is entirely free and lifted clear of the front wall 20.

As best seen in Figure 6, in which a portion of the bottom 23 is broken out to disclose internal detail, it may be noted that the back wall 34 has a wide recessed portion 35 extending from end wall 21 to an undercut slot or edge portion 36 at which point the rear wall 34 thickens and continues to the internally rounded end wall 22, as indicated at 37, the internally-rounded portion 37 serving to accommodate the rounded head portions or bights of the bobby pins to be carried by the device. When the front door 32 and the cover 33 are removed, a special pack unit or magazine, generally indicated at 38, and shown alone in Figures 14 and 15, may be inserted by sliding the same vertically downwardly between front and rear walls 20 and 34 in such fashion that the rear rim or wall 39 will be seated against the recessed portion 35 of rear wall 34 between end wall 21 and the undercut edge 36 with a projecting end or edge 40 thereof extending beneath the undercut edge 36. The mentioned pack magazine or frame 38 is transversely substantially U. shape in section, with an end wall 41 connected at right angles to the rear wall 39 and to said end wall 41 is connected a front wall 42 fitting within the front wall 20 of the dispensing container 18 and extending toward the other end wall 22 of the container slightly further than the length of the previously-mentioned rear wall 39 of the pack frame 38. Upon this rear wall 39 of member 38 is an inwardly-projecting retainer or ridge 43. Vertically along the intermediate portion of end wall 41 of the mentioned pin pack member 38 is integrally mounted a separating member 44 which is substantially wedge-shaped in cross-section and at the lower end projecting at 45 a short distance below the lower end of the front and rear walls 39 and 42.

The bottom 23 of the dispenser 18 terminates not only a distance short of end wall 21, but actually short of meeting with the lower end 45 of the wedge-shaped spreader 44 extending down substantially to the level of the upper surface of bottom 23 intermediate the front and rear walls 42 and 39 of the pack member as well as the front and rear walls 20 and 34 of the dispenser as a whole. In order to expose a portion of the mentioned lower end 45 of the spreader, the front and rear walls 20 and 34 are cut back from the side or end wall 21 a short distance, while the end wall 21 itself is also terminated a short distance above the level of bottom 23 in order to provide the dispensing opening 24 primarily provided by the short end 46 of said bottom.

The purpose of the pack frame or member 38 is to retain a stack of bobby pins 47 between the projecting retaining edge or ridge 43 on the rear wall thereof and the front wall 42 in such fashion that straight legs 48 of the pins, as indicated in Figure 15, will extend into the space 49 between the front wall 42 and the substantially parallel side of wedge-shaped member 44, while the inclined undulated legs 50 will engage against the inclined surface 51 of member 44 within rear wall 39 of magazine or pack member 38. Projecting ridge or retainer 43 engages against intermediate portions of the pins to hold them against front wall 42. In the front and rear walls 20 and 34 of the dispenser proper are a pair of longi-

tudinal slots 53, 54 disposed immediately above bottom 23 and correspondingly opposite to each other, an oblong slide member 55 being transversely disposed in the slots with a pair of finger pieces 56 and 57 secured exteriorly upon the slide member in exposed positions exteriorly of front and rear walls 20 and 34, so as to be manually accessible for sliding this member along the slots toward the separator 44. The mentioned slide member 55 has a seat or recess 58 for receiving the head end 59 of the lowermost pin in the stack 47, the recess 58 having a rearwardly-arcuate form, as indicated at 60, to conform generally with a rounded head end or bight of the pin to be seated therein for dispensing from the device. In the lower portion of end wall 22 is an opening 61 through which the lower end 62 of a pendently attached spring 63 extends inwardly and abuts the end of slide or pusher member 55, the spring being attached at the upper outer side thereof by means of a pair of screws or rivets 64 to end wall 22 and seated in a recess or channel 65 in the mentioned end wall. The arrangement is such that normally the inner portion 66 of the lower end 62 of spring 63 resiliently retains the pusher 55 in such position that the upper surface 68 thereof is disposed beneath the stack 47 of the bobby pins to support the latter in stored condition within the dispenser, but the slider slots 53 and 54 extend far enough to the right beneath the lower end of end wall 22 to allow the pusher to be shifted manually a short distance to the right of its normal idle position, as indicated in Figure 5. In this figure it is evident that the pusher 55 may be moved sufficiently to cause spring 63 to extend at the lower end 62 thereof outwardly from the groove or channel 65, while the pusher then occupies a position in which the recess 59 registers with the rounded end or bight 59 of the lowermost pin 67 so that the entire stack will tend to drop into a lower position a distance equivalent to the width of one pin. In the mentioned position of the lowest pin 67, the latter is clear of the lower end of the package frame 38, except for the downward extension 45 of spreader 44 which still remains in the path of the open end of the bobby pin at the left side of the apparatus. If at this time the pusher is shifted toward the separator 44 by means of finger pieces 56 and 57 which are easily accessible upon the front and rear of the device adjacent to the lower end of end wall 22, the result will be that the lowermost bobby pin 67 will be pushed first in such manner against the separator 44 as to separate the legs 48 and 50 thereof to a predetermined extent along the straight and inclined sides of spreader 44 in opening 24 of the dispenser so that the pin will be manually accessible for withdrawal in a downwardly-inclined direction from the dispenser.

It is self-evident that the packing frame 38, or magazine, may only serve to first form the means by which to introduce the entire stack of pins into the dispenser and thereafter to retain the open ends of the legs in place, but must in no case block the slider slots 53 and 54. The mentioned frame or magazine member 38 must therefore be suspended within the front and rear walls 20 and 34 and end wall 21 of the dispenser in an upper recess or shoulder portion 69 by means of an upper marginal flange 70 which extends along the upper edge of rear wall 39, end wall 41, and a portion of the length of the front wall 42 of the magazine or package frame 38. In addition, a practical feature included in the construction is the provision of a follow-up member or

balancing member 71 adapted to rest on the upper end of bobby pin stack 47, a multi-loop spring 72 having the upper end thereof secured in an aperture at 73a in top 33 of the dispenser, while the lower end at 74a is engaged in an aperture in the upper surface of balancing member 71 in such manner as to exert resilient pressure on the stack 47 within the dispenser, to feed the pins downwardly. When a bobby pin 67 has thus been dispensed from the device, the pusher 55 is not brought entirely the extreme distance to the right which would cause another pin to engage with the head portion thereof in recess 58 on the pusher, but rather, the latter is allowed to stop against the inner lower end 66 of spring 63 until another pin may be required for use. Thus, in the meantime, the pins rest upon the upper surface 68 of the pusher until the latter is again shifted to the right to register a further pin in the recess for being pushed and thereby dispensed from opening 24 in the lower left portion of the dispenser.

My bobby pin dispenser is also susceptible of assuming another form in which the bobby pin package frame or guide member is capable of retaining a stack of bobby pins associated therewith in a special manner by engaging both ends thereof frictionally, which member is shown in perspective in Figure 11 and in actual operative position within the dispenser in Figure 10. Thus, as also disclosed in Figure 9, a dispenser, generally indicated at 72, is provided with a rear wall 73 and end walls 74, 75 extending forwardly therefrom, and at the forward edges of the latter walls are integral opposite marginal portions 76, 77 having the opposite interior recesses 78, 79 for slidably receiving the vertical tongues 80, 81 of a vertically slidable front door 82 to which a top or cover 83 is integrally secured to serve as a closure for the top of the dispenser for closing the same when the front door 82 is in its closed position upon the front of the device. In the lower end of the front door 82 is an open slot 84 immediately above the bottom 85, while in the rear wall 73 is a corresponding slot 86 for the slider 55 which is controlled in this form of the invention in the same manner as already described by means of finger pieces 56 and 57. A retaining spring 63 is mounted in a vertically-directed groove or channel 65 in the end wall 75 with the lower inwardly-extending end 62 having the inner end 66 resiliently abutting the outer side of pusher 55 through the opening 87 in the lower portion of wall 75 in a position to allow the pusher 55 to be manually shifted toward end wall 75 with incident projection of spring 63 from groove 65 therein in order to register recess 58 on the pusher with the bight 59 of the lowermost bobby pin 67 within the dispenser.

However, in the present form of the invention, the magazine pack or frame, generally indicated at 88, has a thin resilient rear wall 89 which is normally arcuate in form and at the right end is enlarged to form the externally flat wall 90 with a forwardly and inwardly-disposed retaining flange 91, while within the latter this end wall is formed with an arcuate curvature 92 adapted to receive the curved heads or bights 59 of the bobby pins. At the other end the resilient arcuate rear wall 89 is formed into an opposite flat end wall 93 upon the intermediate interior portion of which is integrally mounted a wedge-shaped spreader 94 having the rear surface 95 thereof substantially at right angles with the exterior of wall 93, while the forwardly-disposed

surface 96 is inclined toward the right in rearward direction. At the bottom, the separator 94 is extended to form the lower projecting end 97. The arrangement is such that when member 88 is inserted into the dispensing container 72, the end walls 90 and 93 will be disposed immediately within the end walls 75, 74 of the container, respectively, with the lower end 97 of separator 94 exposed below the lower end of end wall 74 of the container and beyond the outer end 98 of the container bottom 85, the latter being cut back at 99 intermediate rear wall 73 and slideable front door or closure 82 to provide a dispensing opening, generally indicated at 100, for dispensing the bobby pins from the device.

In this form of the invention, also, means are included for suspending the bobby pin pack or frame. Hence, upon the upper ends of end walls 90 and 93 are provided a pair of outwardly-projecting suspension flanges 101, 102 adapted to be seated in the end recesses 103 and 104 in end walls 75 and 74, respectively, of the dispensing container, as indicated in Figure 9. The pack frame or magazine 88 is necessarily thus suspended in order that the lower end thereof will clear the slots 84 and 86 and allow slider 55 to slide freely in said slots and dispense the bobby pins one by one out through opening 100, as already described in connection with the first form of the invention disclosed in connection with Figures 1 to 6.

However, a special feature of this form of the invention is that the pin pack unit or magazine 88 normally has the rear wall 89 thereof arched to such an extent that end walls 90 and 93 are brought closer together than the actual length of a bobby pin so that the ends or bights 59 and the ends of the straight legs 48 engage against the inner arcuate portion 92 of end wall 90 and 105 of end wall 93, so that the entire stack 47 thereof is held at the ends by friction, or virtually a clamping effect of the end walls upon the bobby pins. It is to be noted that the width of the rear wall 89 of the magazine 88 is greater than the width of the space defined by the rear wall 73 and end walls 74 and 75 of the dispenser 72. Thus when the magazine 88, with the bobby pins held therein, is inserted into container 72, the front flange 91 of end wall 90 and the front flange 106, when forced into the container to engage upon the rear surfaces of the forward flanges 76 and 77 of the container, will tend to partly flatten the rear wall 89 against rear wall 73 of the container, while insertion of the door 82 with its inner edges engaging against flanges 91 and 106 tends to spread them apart, thus releasing the end walls 90 and 93 from frictional or clamping contact with the ends of the bobby pins so that they are in released condition to be individually dispensed by engagement with recess 58 in pusher 55 for propulsion out through the dispensing opening 100 of the dispenser, as already intimated.

Preferably, the dispenser, as well as the frames, units, or pack members 38, 88, may be made of plastic, die cast metal or any material suitable for the purpose, and such materials are merely suggested, as any material which will serve the purpose may be freely used for making the apparatus in any of the forms described.

Manifestly, variations may be resorted to and parts and features may be modified or used without others within the scope of the appended claims.

Having thus fully described the invention, I claim:

1. A pin dispenser comprising a dispensing container open at its top, said container having an opening in the bottom extending inwardly from one end wall thereof, a pin frame having a stack of U-shaped pins supported therein insertable in said container through the open top thereof, said pin frame when inserted in said container having the ends of the legs of said pins adjacent to said one end wall of the container and having the bights adjacent to the other end wall of the container, there being an opening in the bottom of said frame extending inwardly from one end wall thereof adjacent to said one end wall of said container and in registry with the opening in said container, a spreading member projecting inwardly from the interior of said one wall of said frame and extending between and bearing against the ends of the legs of at least several of the pins in said stack, a slide member extending transversely through said container and supportingly receiving the bight of the lowermost pin of said stack, said slide member being arranged adjacent the bottom of said container inwardly of the other end of the latter and mounted in said container for sliding movement toward and away from the bottom opening in said container, and a cover resting upon the open top of said container for closing the open top of said container.

2. A pin dispenser comprising a dispensing container open at its top, said container having an opening in the bottom extending inwardly from one end wall thereof, a pin frame having a stack of U-shaped pins supported therein insertable in said container through the open top thereof, said pin frame when inserted in said container having the ends of the legs of said pins adjacent to said one end wall of the container and having the bights adjacent to the other end wall of the container, there being an opening in the bottom of said frame extending inwardly from one end wall thereof adjacent to said one end wall of said container and in registry with the opening in said container, a spreading member projecting inwardly from the interior of said one wall of said frame and extending between and bearing against the ends of the legs of at least several of the pins in said stack, a slide member extending transversely through said container and supportingly receiving the bight of the lowermost pin of said stack, said slide member being arranged adjacent the bottom of said container inwardly of the other end of the latter and mounted in said container for sliding movement toward and away from the bottom opening in said container, spring means operatively connected to the other end wall of said container and engaging said slide member for biasing the latter to a position for supportingly receiving the bight of the lowermost pin of said stack, and a cover resting upon the open top of said container for closing the open top of said container.

3. A pin dispenser comprising a dispensing container open at its top, said container having an

opening in the bottom extending inwardly from one end wall thereof, a pin frame having a stack of U-shaped pins supported therein insertable in said container through the open top thereof, said pin frame when inserted in said container having the ends of the legs of said pins adjacent to said one end wall of the container and having the bights adjacent to the other end wall of the container, there being an opening in the bottom of said frame extending inwardly from one end wall thereof adjacent to said one end wall of said container and in registry with the opening in said container, a spreading member projecting inwardly from the interior of said one wall of said frame and extending between and bearing against the ends of the legs of at least several of the pins in said stack, said slide member being arranged adjacent the bottom of said container inwardly of the other end of the latter and mounted in said container for sliding movement toward and away from the bottom opening in said container, a spring means operatively connected to the other end wall of said container and engaging said slide member for biasing the latter to the position for supportingly receiving the bight of the lowermost pin of said stack, a cover resting upon the open top of said container for closing the open top of said container, a follower normally resting upon said stack, and resilient means operatively connected to said cover and said follower for urging the pins of the stack downwardly.

4. A pin dispenser comprising a dispensing container open at its top, said container having an opening in the bottom extending inwardly from one end wall thereof, a pin frame having a stack of U-shaped pins supported therein insertable in said container through the open top thereof, said pin frame when inserted in said container having the ends of the legs of said pins adjacent to said one end wall of the container and having the bights adjacent to the other end wall of the container, there being an opening in the bottom of said frame extending inwardly from one end wall thereof adjacent to said one end wall of said container and in registry with the opening in said container, a spreading member projecting inwardly from the interior of said one wall of said frame and extending between and bearing against the ends of the legs of at least several of the pins in said stack, a slide member extending transversely through said container and supportingly receiving the bight of the lowermost pin of said stack, said slide member being arranged adjacent the bottom of said container inwardly of the other end of the latter and mounted in said container for sliding movement toward and away from the bottom opening in said container, a finger piece exteriorly of said container and operatively connected to each end of said slide member for effecting sliding movements of the latter, and a cover resting upon the open top of said container for closing the open top of said container.
